UNITED STATES PATENT OFFICE.

THOMAS CORROW, OF SWAMPSOFT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

ROUNDING AND CHANNELING MACHINE.

1,269,055.

Specification of Letters Patent. Patented June 11, 1918.

Application filed August 20, 1917. Serial No. 187,114.

To all whom it may concern:

Be it known that I, THOMAS CORROW, a citizen of the United States, residing at Swampscott, in the county of Essex and 5 State of Massachusetts, have invented certain new and useful Improvements in Rounding and Channeling Machines; and I do hereby declare the following to be a full, clear, and exact description of the invention, 10 such as will enable others skilled in the art to which it appertains to make and use the same.

The invention relates to machines for rounding or rounding and channeling the 15 soles of shoes after the outsole has been temporarily secured in position preparatory to permanently sewing or otherwise securing it to the shoe.

The invention is intended primarily as an 20 improvement in the rounding and channeling machine shown and described in Patent No. 1,030,606, June 25, 1912, although it may be embodied with advantage in other rounding machines. Machines of this type are 25 provided with feeding devices which act on the projecting edge of the shoe sole, and with guides which engage the crease or engage 30 the upper close to the crease and position the shoe with relation to the chopping knife which trims its edge. The operator holds the shoe and directs it to the guides during the feed, and he usually gives the shoe a slight "lead" in order that it may be maintained snugly against the guides during 35 the feed. The edge of the chopping knife is parallel to the line of action of the feeding devices however, and therefore at an angle to the line of movement of the sole edge when the shoe is given a lead, and this angle 40 increases with an increase in the lead. An objectionable serrated edge will therefore be formed when the shoe is given a material lead to insure its constant engagement with the guides.

45 It is one of the objects of the present invention to avoid this objectionable feature of the prior constructions; and to this end one feature of the invention contemplates so mounting the chopping knife that its edge 50 is inclined to the line of action of the feeding devices. The edge may thus be so arranged that it will be parallel to the travel or feed of the sole edge when the shoe is given a lead corresponding to the angle of

the knife, thus permitting the sole edge to 55 be trimmed in a more satisfactory manner and with less skill and care on the part of the operator. The amount of lead habitually given to the shoe will vary with different operators, and a further feature of the 60 invention contemplates the provision of means for varying the angle of the knife edge in accordance with the lead which it is desired to give the shoe.

The various features of the invention will 65 be understood from an inspection of the accompanying drawings and the following detailed description of the mechanism illustrated therein.

In the drawings, Figure 1 is a front elevation showing so much of a rounding and channeling machine as is necessary to illustrate the application of the present invention thereto; Fig. 2 is a detail plan view, partly in section, on line 2 of Fig. 3, showing the carrying slide on which the chopping knife is mounted detached from the machine; Fig. 3 is a front end view of the knife carrier slide and knife securing devices; and Fig. 4 is a sectional view on line 4, Fig. 2. 70

In the drawings the invention is illustrated as embodied in the machine shown and described in the patent above referred to. This machine is provided with a crease guide 2 for guiding the shoe when operating 85 through the shank, with a forepart guide 4 movable vertically into and out of engagement with the shoe for guiding the shoe during the operation about the forepart, with a 4-motion feeding jaw 6, and with an oscillating sole support 8 carrying the channeling knife 10. The machine is also provided with a reciprocating slide 12 which carries the edge trimming chopping knife 14. The knife is secured on the lower side of the slide 90 by two clamping plates 16 and 18 arranged to engage the opposite beveled edges of the knife. The plate 16 carries at its forward end the scoring knife 20, and is secured in position by a bolt 22 passing through a slot 100 in the plate and engaging the lug 24 which projects from the lower side of the carrier slide. The clamping plate 18 which engages the opposite edge of the knife is provided with a groove 26 within which the beveled 105 edge of the knife fits, and is mounted for vertical adjustment on a guideway 28 formed on the side of the lug 24. The plate

105

18 is held in adjusted position by a screw 30 passing through a slot 32 in the plate and engaging the lug 24. A washer 34 is interposed between the head of the bolt and the 5 face of the clamping plate.

By adjusting the clamping plate 18 vertically, one side edge of the knife may be raised or lowered with relation to the opposite side edge to vary the inclination of its 10 front or cutting edge 36. The knife may be thus secured in position on the knife carrier slide with its cutting edge at an inclination to the line of action of the feed jaw and in such position that it will be parallel to 15 the travel of the sole edge when the shoe is given a lead which will insure its proper travel against the guides during the operation about the shoe. This manner of securing the knife to the carrier slide also enabling the angle of the knife edge to be 20 readily varied in accordance with the lead which any particular operator habitually gives the shoe in directing it to the guide. The arrangement of the knife edge at an 25 inclination to the direction of action of the feeding devices corresponding to the lead given to the shoe by the operator results in the formation of a comparatively smooth and uniform edge, and permits the lead to be increased without impairing the quality 30 of the work. Less care and skill is therefore required to properly guide the shoe than with the prior constructions in which the knife edge is parallel to the line of action 35 of the feeding devices, and in which any substantial lead of the shoe results in an uneven and defective sole edge.

While the invention is intended primarily as an improvement in rounding and channelling machines, and has been shown and 40 described as embodied in such a machine, it will be understood that it is not confined in its application to such machines, but may if found desirable be embodied in other shoe 45 machines.

While it is preferred to employ the specific construction and arrangement of parts, particularly in embodying the invention in the machine of the patent above referred to, 50 it will be understood that this construction and arrangement is not essential to the broader features of the invention, but may be varied or modified as found desirable or best suited to the construction of the machine in which it is to be embodied.

Having explained the nature and object of the invention, and specifically described one form of mechanism in which it may be embodied, what is claimed is:—

60 1. A sole rounding machine, having, in combination, shoe feeding and guiding

means, and a chopping knife for trimming the edge of the sole having its cutting edge inclined in the direction of the feed to compensate for the lead given the shoe by the 65 operator.

2. A sole rounding machine, having, in combination, feeding devices, guides against which the operator leads the shoe during the feed, and a chopping knife having its 70 cutting edge at an angle to the line of action of the feeding devices.

3. A sole rounding machine, having, in combination, shoe feeding and guiding means, a knife carrier, and means for securing a chopping knife in the carrier having provision for varying the angle of its cutting edge with relation to the line of action 75 of the feeding means.

4. A sole rounding machine, having, in combination, feeding devices, guides against which the operator leads the shoe during the feed, a chopping knife, and means for varying the angle of its cutting edge in accordance with the lead to be given to the 80 shoe.

5. A sole rounding machine, having, in combination, feeding devices, guides against which the operator leads the shoe during the feed, a reciprocating knife carrier, and means for securing a knife in the carrier and for varying the inclination of its cutting edge to the line of action of the feeding 90 devices.

6. A sole rounding machine, having, in combination, guides for the shoe, a reciprocating feed jaw, a reciprocating knife carrier, and clamps on the carrier for engaging the side edges of the chopping knife, one of which is adjustable to vary the angle of the 100 knife edge.

7. A shoe machine, having, in combination, feeding and guiding means, and a chopping knife having its cutting edge inclined in the direction of feed to compensate for the lead given to the work in directing 105 it to the guiding and feeding means.

8. A shoe machine, having, in combination, feeding and guiding means, a knife carrier, and means for securing a chopping 110 knife in the carrier having provision for varying the angle of its cutting edge with relation to the line of action of the feeding means.

9. A shoe machine, having, in combination, feeding devices, guides against which the operator leads the work during the feed, a reciprocating knife carrier, and means for securing a knife in the carrier and for varying the inclination of its cutting edge to the 120 line of action of the feeding devices.

THOMAS CORROW.
